US0D1050479S

(12) **United States Design Patent** (10) Patent No.: **US D1,050,479 S**
(45) Date of Patent: ** Nov. 5, 2024

(54) **DIAGNOSTIC TESTING APPARATUS FOR MEDICAL OR LABORATORY PURPOSES**

(71) Applicant: **SHANGHAI RUIYU BIOTECH CO., LTD.**, Shanghai (CN)

(72) Inventor: **Rui Chen**, Shanghai (CN)

(**) Term: **15 Years**

(21) Appl. No.: **35/517,120**

(22) Filed: **May 9, 2022**

(80) **Hague Agreement Data**

Int. Filing Date: **May 9, 2022**

Int. Reg. No.: **DM/222813**

Int. Reg. Date: **May 9, 2022**

Int. Reg. Pub. Date: **May 12, 2023**

(51) LOC (14) Cl. **24-02**

(52) U.S. Cl.

USPC **D24/216**

(58) **Field of Classification Search**

USPC D24/216, 217, 107, 185, 186, 219, 231, D24/232, 233, 234; D10/81

CPC G01N 2035/00306; G01N 2035/00326; G01N 2035/00336; G01N 2030/027; G01N 21/76

See application file for complete search history.

(57) **CLAIM**

The ornamental design for a diagnostic testing apparatus for medical or laboratory purposes as shown and described.

DESCRIPTION

1.1 : Perspective

1.2 : Front

1.3 : Back

1.4 : Left

1.5 : Right

1.6 : Top

1.7 : Bottom

1.8 : Enlarged

2.1 : Perspective

2.2 : Front

2.3 : Back

2.4 : Left

2.5 : Right

2.6 : Top

2.7 : Bottom

2.8 : Enlarged view

1. The title of product incorporating the design: Diagnostic testing apparatus for medical or laboratory purposes. 2. The drawing designated to best show the essential features of the design: the perspective view 1.1. 3. The broken lines shown in the figures depict portions of the diagnostic testing apparatus for medical or laboratory purposes that form no part of the claimed design; the dash-dot broken lines in the figures are demarcating enlarged areas and form no part of the claimed design.

1 Claim, 16 Drawing Sheets
